UNITED STATES PATENT OFFICE.

PAUL J. HILGENDORF, OF HOPKINTON, IOWA.

OFFICE-INDICATOR.

SPECIFICATION forming part of Letters Patent No. 684,820, dated October 22, 1901.

Application filed March 19, 1901. Serial No. 51,910. (No model.)

To all whom it may concern:

Be it known that I, PAUL J. HILGENDORF, a citizen of the United States, residing at Hopkinton, in the county of Delaware and State of 5 Iowa, have invented a new and useful Office-Indicator, of which the following is a specification.

The invention relates to improvements in office-indicators.

10 The object of the present invention is to improve the construction of office-indicators and to provide a simple, inexpensive, and efficient one capable of ready adjustment and adapted to display a variety of information 15 for indicating the whereabouts of a person, the time of his return to the office, and the like.

The invention consists in the construction and novel combination and arrangement of 20 parts hereinafter fully described, illustrated in the accompanying drawings, and pointed out in the claim hereto appended.

In the drawings, Figure 1 is an elevation of 25 an office-indicator constructed in accordance with this invention and partially broken away to show a portion of one of the rotary disks. Fig. 2 is a similar view showing another arrangement of the parts. Fig. 3 is a vertical sectional view on the line 3 3 of Fig. 1. Fig. 30 4 is a detail view of the oscillatory indicator.

1 designates a cardboard body provided with an approximately centrally arranged opening 2, adapted to display or expose a portion of the surface of a rotary disk or plate 3, 35 which is preferably constructed of cardboard; but the body and the disk or plate 3 may, if desired, be constructed of any other suitable material. The disk or plate 3 co-operates with a second disk or plate 4, which is exposed 40 through an aperture 5, located at one side of the body, as clearly illustrated in Figs. 1 and 2 of the drawings. The upper or smaller disk or plate is designed to contain such matter as "The doctor will return at," "Can be 45 found at," "Will return soon," and similar expressions, and they may be applied to the face of the disk or plate 3 in any suitable manner.

The lower or larger disk or plate, which is 50 partially exposed through the aperture 5, is designed to contain a large amount of information, and it extends a short distance be-

yond the side of the body to enable it to be readily rotated to bring any matter on its surface opposite the aperture 5. This lower disk, 55 which is designed to be read in connection with the exposed portion of the upper disk or plate, is designed to be provided with the hours, which are successively arranged and which may be brought to the aperture 5, as 60 indicated in Fig. 1, so that the indicator will read that the doctor or the person will return at the designated time. Other information—such as "Hall," "Barber," "Church," "Court-house," "Drug-store," "Bank," and 65 the like—may be provided, and the disk or plate 4 is adapted to be rotated to bring any word or expression on its face opposite the aperture 5, and the indicator may be arranged as shown in Fig. 2, one of the disks or plates 70 displaying "Can be found at" and the other disk or plate showing the word "Bank." It will be clear that a large amount of information may be arranged in convenient position to be readily exposed to indicate the whereabouts of a person, or the time when he will 75 return, or the like, and the indicator is designed to be provided with suitable devices or words for calling attention to the information displayed, and it may contain additional 80 information to indicate the office-hours, the telephone-number, and the like.

In order to enable the information to be compactly arranged and to economize the space of the lower disk or plate 4, an oscillatory indicator 6 is arranged to move transversely of the aperture 5 to arrange the number "30" over the face of the disk or plate 4 to change from the hour to the half-hour. The disk or plate 4 is designed to be provided only with the hours, which will be arranged as follows: "1.00 P. M.," "2.00 P. M.," "3.00 P. M.," "4.00 P. M.," &c. When it is desired to indicate the half-hour, the transversely-movable indicator 6 is swung upward 90 to arrange the "30" over the two ciphers, as indicated in Fig. 1 of the drawings, and the said indicator 6 is adapted to be moved downward or backward to the position indicated by dotted lines in Fig. 2. The transversely-movable indicator, which is approximately L-shaped, as illustrated in Fig. 4, is provided at one end with a perforation 7 for the reception of a pivot 8, and its other end 9 carries

the number "30," which is exposed, as before explained, when the transversely-movable indicator is raised, as shown in Fig. 1. The indicator 6 is provided at its angle with a knob 5 or head 10, connected with the indicator by a stem, which is arranged in a curved slot 11 of the body, whereby the movement of the indicator 6 is limited. The knob or head is also adapted to be grasped to operate the indicator 6.

It will be seen that the office-indicator is exceedingly simple and inexpensive in construction, that it is adapted to contain a large amount of information, and that the same 15 may be varied to adapt the indicator for the use to which it is to be applied. It will also be seen that the transversely-movable indicator is adapted to be readily shifted to expose a portion of its surface at the aperture 6, and that it will dispense with the half-hours 20 on the disk or plate 4, and will thereby enable the space of the same to be economized.

What I claim is—

An office-indicator comprising a body pro-

vided with the aperture 5 and having a short 25 curved slot arranged adjacent to the aperture, a rotary plate mounted on the body at the back thereof and located beneath the aperture 5 and adapted to be exposed thereat, the L-shaped transversely-disposed oscillatory indicator located at the said slot and pivoted at one end to the body, its other end being arranged to swing to and from the aperture 5 and adapted to cover a portion thereof, whereby a portion of the surface of the oscillatory indicator is exposed, and the knob or head provided with a stem extending through the slot and connected with the indicator at the angle thereof, substantially as and for the purpose described.

In testimony that I claim the foregoing as my own I have hereto affixed my signature in the presence of two witnesses.

PAUL J. HILGENDORF.
